UNITED STATES PATENT OFFICE.

FREDERICK H. LANG, OF COLUMBUS, OHIO.

MEANS FOR EXTINGUISHING FIRES IN VESSELS.

1,378,964.

Specification of Letters Patent. Patented May 24, 1921.

Application filed July 6, 1920. Serial No. 394,111.

To all whom it may concern:

Be it known that I, FREDERICK H. LANG, a citizen of the United States, residing at Columbus, in the county of Franklin and 5 State of Ohio, have invented a certain new and useful Improvement in Means for Extinguishing Fires in Vessels, of which the following is a specification.

This invention relates to means for extinguishing fire in gasolene washer chambers such as used by "dry cleaning" establishments. Such chambers are necessarily opened frequently and are often left open for considerable periods of time thereby exposing the gasolene to the danger of ignition.

The object of the invention generally is to provide improved means for automatically and promptly closing the cover of the chamber in the event of ignition and particularly to provide means whereby the normal operation of the cover in opening and closing the same shall not involve the operation of other parts.

25 The invention is embodied in the example herein shown and described, the features of novelty being finally claimed.

In the accompanying drawings—

Figure 1 is a view in end elevation with 30 the cover of the washer chamber raised.

Fig. 2 is a rear elevation of the same.

In the views of the drawing the character 5 designates the washer chamber or tank and 5^a the cover therefor. In rear of 35 the washer is erected a bracket having a vertical part 6 and a horizontal portion 6^a that extends toward the front over the opening of the chamber. Erected parallel and secured to the vertical part 6 of the bracket 40 is a rod 7. Slidable on the rod 7 is a weight 8 normally supported in elevated position by one arm 9 of a bell crank lever, the other arm 9^a of said lever being held, when the lever is in weight supporting position,

45 by means of a wire 10 stretched between the arm 9 and the forward end of the horizontal portion 6^a of the bracket. The wire 10 contains one or more fusible members 11 located to be melted by the heat 50 generated in the event the gasolene of the washer is ignited.

Connected with the vertical part of the bracket is a pusher 12 having a head 12^a at its forward end and a stop pin 12^b at its 55 rear end. Between the pusher head 12^a and the bracket is a coil spring 13 tending to

press the pusher forward, but normally the pusher is held rearward with the spring compressed by means of a pivoted latch 14 engaging a notch in the pusher stem.

The outer arm of the latch 14 is located below and in the path of the weight 8 so that when the latter is released in case of fire the latch 14 is thrown to release the pusher.

60 The pusher head is located so as to be near the cover 5^a when the latter is in open position as best shown in Fig. 1. It is preferable that the cover shall rest when opened in close proximity to the pusher and in a 70 slightly inclined position rearward as for example against a bracket 5^b secured on the chamber. This permits the cover to be operated ordinarily without operating any of the other mechanism. From the construction thus far described it is obvious that when fire occurs in an open washer the wire containing the fusible members is severed thereby permitting the weight 8 to fall and strike the latch 14 thus releasing the pusher which thus impels the cover to closing position.

75 At the rear of the washer is shown a tank 15 to contain a fire extinguishing material or materials for generating an extinguishing material as well understood. Said tank communicates with the interior of the washer chamber above the gasolene level by means of a pipe 15^a. The tank 15 is provided with plunger 16 located to be struck 80 by the falling weight 8 after it passes the latch 14 to release the extinguishing material to the washer and nearly at the same time with the closing of the cover. The extinguishing material and the mechanism for 85 releasing the same to the washer tank can be of any suitable variety and form.

90 The forms of the parts can be changed without departing from the gist of the invention as claimed.

95 What I claim is:

1. Means for closing the cover of a chamber such as described comprising, in combination, a weight, thermally controlled means for supporting the weight, a spring 105 actuated pusher to act on the cover if in opened position, and a latch to hold said pusher under tension in operative position, said latch located to be released by the weight when the latter falls.

110 2. In means of the kind described, the combination with a chamber and a cover

therefor, of means for closing the cover including a pusher unconnected with the cover, and thermally controlled means for causing the actuation of the pusher to close the cover in the event of fire in the chamber.

5 3. In means of the kind described, the combination with a chamber and a cover therefor hinged to stand by its own weight in open position, of means for closing the 10 cover including a pusher unconnected with the cover, and thermally controlled means for causing the actuation of the pusher to close the cover in the event of fire in the chamber.

15 4. In means of the kind described, the combination with a chamber and a cover therefor hinged to stand by its own weight

in open position, of means for closing the cover including a pusher unconnected with the cover, a latch for holding said pusher in 20 operable position and a thermally controlled weight for releasing said latch in the event of fire in the chamber.

5. In means of the kind described, the combination with a chamber and a **cover** 25 therefor hinged to stand by its own weight in open position, of means for closing the cover including a pusher, a weight for causing the actuation of the pusher, and thermally controlled means for holding said 30 weight in elevated position and to release the same to close the cover in case of fire in the chamber.

FREDERICK H. LANG
